UNITED STATES PATENT OFFICE

128,657

DESIGN FOR AN ANIMAL SHOE OR THE LIKE

Jay Wheeler, Sacramento, Harry C. McKim and
Hollis T. Riley, Huntington Park, Calif.

Application July 31, 1939, Serial No. 86,390

Term of patent 14 years

To all whom it may concern:

Be it known that we, Jay Wheeler, Harry C. McKim, and Hollis T. Riley, citizens of the United States, and residents of the city of Sacramento, city of Huntington Park, and city of Huntington Park, in the county of Sacramento, county of Los Angeles, and county of Los Angeles, and State of California, have invented a new, original, and ornamental Design for an Animal Shoe or the Like, of which the following is a specification, reference being had to the accompanying drawing, forming part thereof.

Fig. 1 of the drawing is a plan view of the animal shoe showing our new design.

Fig. 2 is a perspective view thereof.

Our new shoe design is characterized by the abrupt slope, in a single plane, at the toe front of the shoe and the gentle slope on the rear side of the toe front.

We claim:

The ornamental design for an animal shoe or the like, substantially as shown and described.

JAY WHEELER.
HARRY C. MCKIM.
HOLLIS T. RILEY.
